PILING SECTION

Gerald G. Greulich, Mount Lebanon, Pa.

Application September 27, 1935, Serial No. 42,472

4 Claims. (Cl. 61—60)

This invention relates to piling sections, and more particularly to sheet piling which is provided on its edges with interlocking hooks.

One of the objects of the present invention is the provision of a novel piling section which is very durable, it being heavily reinforced where it is subjected to the greatest abuse.

Another object is to provide a device of the class described which, when used with a similar device, enables their outer surfaces to lie in a single plane, ample clearance being provided for slight rotation at their connection.

A further object is to provide a piling section which may be easily and cheaply rolled, of minimum weight, and provides a long angular water seal when interlocked with a similar device.

These and further objects will be apparent after referring to the drawing, in which:

Figure 1 is a plan of the piling section of the invention.

Figure 2 is an enlargement of the left-hand side portion of the piling section of Figure 1.

Figure 3 is an enlargement of the right-hand side portion of the piling section of Figure 1.

Referring more particularly to the drawing, the numeral 2 designates the web of the piling section of the invention which has its side faces 3 and 4 in parallelism, thus providing a constant wall thickness, as shown at a. A flange 5 is formed integral with and extending at right angles to the web 2, and has its side faces 6 and 7 in parallelism, thus providing a wall thickness b of constant cross-section. Another flange 8 is formed integral with the other end of the web 2 and extends at right angles with respect thereto in a direction which is opposite to the flange 6. The flange 8 has its side faces 9 and 10 in parallelism, providing a wall thickness c of constant cross-section.

It is to be noted that the thicknesses of the walls of the flanges 5 and 8, as shown at b and c, respectively, are substantially greater than the thickness a of the web 2, which makes for lightness of construction, as a lesser displacement can be had in the web without jeopardizing the strength of the piling section.

The terminal end of the flange 5 is enlarged, as at 12, and extends at right angles to its longitudinal axis, and is of such cross-section as to provide a terminal surface 13 which is at slightly less than an included angle of 90 degrees with respect to the longitudinal axis of the flange 5.

The terminal surface 14 of the enlarged portion 12 of the flange 5 is in a plane which converges on the axis of the flange 5 and has a side

face 15 which provides an included angle of less than 90 degrees with respect thereto, thus making a "reentrant" angle. The flange 5 is provided with an enlarged portion 17, adjacent its enlarged portion 12, which carries an extending lip 18, forming a socket 19 therebetween over which the lip extends for at least half of its width.

The terminal extremity of the flange 8 has a surface 22 which provides an included angle of 10 less than 90 degrees with respect to its longitudinal axis. The terminal extremity of the flange 8 is also provided with an enlarged portion 21. This enlarged portion 21 carries a curved hook member 23 which terminates in an enlarged 15 head 24. The inner surface of the head 24 is at an included angle of less than 90 degrees with respect to the longitudinal axis of the flange 8 and, together with the terminal surface 22 thereof, and the curved portion 23 of the enlarged 20 portion 21, forms a dove-tailed groove 26.

The enlarged portions 17 and 21 of the terminal ends of the flanges 5 and 8, respectively, each provide a section modulus substantially double their average thicknesses, as indicated at 25 b and c, respectively, at a point spaced from the web sides of the grooves 19 and 26 a distance equal to substantially their average thicknesses. The line e in Figure 2 represents double the thickness of the flange 5 while the line f represents a distance from the web side of its groove which is equal to its average thickness b. Similarly, in Figure 3 of the drawing, the line h represents double the thickness c of the flange 8 while the line i represents a distance from the web side 35 of its groove 26 which is equal to the average thickness c.

Due to the dove-tailed grooves 19 and 26 and the contours of the heads 12 and 24 of adjacent parts, a connection is formed such as will tend 40 to become tighter if adjacent piling sections are subjected to tensile strain, instead of crowding them apart as is the case with conventional devices. This condition is due to the fact that the engaging surfaces of the sides of the grooves 19 45 and 26 form reentrant angles with respect to the face of the piling section. In addition and as shown in Figure 1, the outside faces of assembled piling sections lie in the same plane or, in other words, their surfaces are "flush". In addition, 50 the engaging surfaces of adjacent piling sections are near their outer faces, as at 7 and 10, in order that secondary stresses are kept at a minimum when the joint is under strain. Furthermore, the long angular path through the joints of adjacent

piling sections provides maximum obstruction to the flow of water, etc.

The neutral axis of the piling section of the invention is substantially at the center of the web 2 and the cross-sectional areas of the ends, or heads, 12 and 24 are substantially constant. The radii of gyration of these ends, or heads, are substantially equal in column strength and the edges of the piling section are proportioned in such 10 manner that each functions as a symmetrical column section.

While I have shown and described one specific embodiment of my invention, it will be understood that I do not wish to be limited exactly 15 thereto, since various modifications may be made without departing from the scope of my invention, as defined by the following claims.

I claim:

1. A piling section comprising a web and flanges 20 extending in opposite directions from said web along its respective longitudinal edges, said flanges having materially greater cross-sectional area at all points than said web and having their outer faces in parallelism with each other, the 25 terminal ends of said flanges being shaped to provide dove-tailed grooves and hooks adapted to interlock with similar parts of an adjacent piling section, each of said flanges being substantially double their average thickness at a point spaced 30 from the web side of said groove a distance equal to substantially its average thickness and tapering toward said web from said point of double thickness to the average thickness thereof and increasing in thickness from said point of double 35 thickness to the web side of said groove.

2. A piling section comprising a web and flanges 40 extending in opposite directions from said web along its respective longitudinal edges, the terminal ends of said flanges being shaped to provide dove-tailed grooves and hooks adapted to interlock with similar parts of an adjacent piling section, each of said flanges being substantially double their average thickness at a point spaced 45 from the web side of said groove a distance equal to substantially its average thickness and tapering toward said web from said point of double thickness to the average thickness thereof and increasing in thickness from said point of double 50 thickness to the web side of said groove.

3. A piling section comprising a web and flanges 5 extending in opposite directions from said web along its respective longitudinal edges, the terminal ends of said flanges being shaped to provide dove-tailed grooves and hooks adapted to interlock with similar parts of an adjacent piling section, each of said flanges being substantially double their average thickness at a point spaced 10 from the web side of said groove a distance equal to substantially its average thickness and tapering toward said web from said point of double thickness to the average thickness thereof and increasing in thickness from said point of double 15 thickness to the web side of said groove, and a lip extending from the web side of one of said hooks and overlying at least one-half of the width of the adjacent dove-tailed groove, whereby the neutral axis of said piling is substantially at the center of the web and the cross-sectional areas of the terminal ends are substantially 20 constant.

4. A piling section comprising a web and flanges 25 extending in opposite directions from said web along its respective longitudinal edges, the terminal ends of said flanges being shaped to provide dove-tailed grooves and hooks adapted to interlock with similar parts of an adjacent piling section, each of said flanges being substantially double their average thickness at a point spaced 30 from the web side of said groove a distance equal to substantially its average thickness and tapering toward said web from said point of double thickness to the average thickness thereof and increasing in thickness from said point of double 35 thickness to the web side of said groove, and a lip 40 extending from the web end of one of said hooks and projecting toward the terminal edge of said flange, said hook being adapted to have interlocking engagement with the hooks of adjacent piling sections and said lip being of such length and angular position as to extend over more than one-half of the width of the adjacent dove-tailed groove, whereby the edges of the piling section 45 are proportioned in such manner that each functions as a symmetrical column section and the radii of gyration of the terminal ends thereof are substantially equal in column strength.

GERALD G. GREULICH. 50
